UNITED STATES PATENT OFFICE.

ORVILLE C. OSTRUM, OF LIVINGSTON MANOR, NEW YORK.

WAGON-BRAKE.

SPECIFICATION forming part of Letters Patent No. 774,364, dated November 8, 1904.

Application filed April 29, 1904. Serial No. 205,589. (No model.)

To all whom it may concern:

Be it known that I, ORVILLE C. OSTRUM, a citizen of the United States, residing at Livingston Manor, in the county of Sullivan and

5 State of New York, have invented certain new and useful Improvements in Wagon-Brakes; and I do hereby declare the following to be a full, clear, and exact description of the invention, such as will enable others skilled in the 10 art to which it appertains to make and use the same.

This invention relates to brakes for wagons and other similar vehicles; and it consists in the novel construction and combination of the 15 parts hereinafter fully described and claimed.

In the drawings, Figure 1 is a plan view of the front axle and running-gear of a wagon, showing the brake in position. Fig. 2 is a side view of the same with one of the wheels 20 removed.

A is the front axle of a wagon or other similar vehicle, and B represents the front wheels journaled on the end portions of the said axle.

C is the running-gear, which is of any approved construction, and D represents the 25 hounds, which project in front of the axle.

E represents guide-brackets secured to the running-gear behind the axle, and e is a brake-beam which is slidable in the said brackets.

30 This brake-beam is provided with brake-blocks on its end portions, which are pressed against the peripheries of the said wheels. F represents two similar levers, which are pivoted on pins f, which pass through the said brackets.

G represents rods which are pivoted to the outer end portions of the said levers. These rods are screw-threaded and are inserted in holes in the end portions of the 35 brake-beam, and f' represents nuts on the

40 screw-threaded portions of the said rods for regulating the position of the brake-beam as the brake-blocks become worn and for connecting the brake-beam with the said rods.

G' is a shaft which passes through the front 45 end portions of the hounds.

H is the wagon-pole provided with a double-forked end portion h, having horizontal slots h', which are normally slidable over the shaft G' between the hounds.

I is a pin which is carried by the forked end 50 portion h behind the shaft G'.

J represents rods the rear ends of which are pivoted to the inner end portions of the levers F by pins j. The front end portions of these rods have plates or links, which are 55 provided with vertical slots i which are slidable upon the pin I. These slots permit the pole to be moved pivotally on the shaft G' without bending the rods, and the said rods are cranked and curved, so as to clear the axle. 60

K represents removable push-pins which are inserted in holes in the forked end portion h of the pole in front of the shaft G'. When these push-pins are in the holes, the wagon can be backed by means of the pole without 65 applying the brake-blocks to the wheels. When the push-pins are removed, the pole slides rearwardly upon the shaft G' and the rods turn the levers on their pivot-pins, so that the brake-blocks are applied to the wheels, 70 and the same action takes place when the wagon is going downhill, because the wagon is forced forward against the resistance of the animals which are harnessed to the said pole.

What I claim is—

1. The combination, with a vehicle running-gear, and front wheels; of a brake-beam provided with a brake-block at each end for bearing against the said front wheels, a longitudinally-slidable draft-pole pivotally connected 80 with the said running-gear and provided with a pin at its rear part, and two rods having their rear ends operatively connected by intermediate mechanism with the said brake-beam and provided at their front ends with 85 vertical slots which engage with the said pin.

2. The combination, with a vehicle running-gear, and front wheels; of a slidable brake-beam supported by the running-gear and provided with brake-blocks for the wheels, levers 90

pivots supported by the running-gear, connections between the outer ends of the said levers and the said brake-beam, a shaft carried by the hounds, a draft-pole provided with 5 longitudinal slots which slide over the said shaft, a pin carried by the said pole and arranged behind the said shaft, and rods pivoted to the inner ends of the said levers and

provided with vertical slots at their front ends which are slidable over the said pin. 10

In testimony whereof I have affixed my signature in the presence of two witnesses.

ORVILLE C. OSTRUM.
